UNITED STATES PATENT OFFICE.

WILLIAM H. THORPE, OF MOUNT VERNON, NEW YORK.

PORTABLE LAMP.

Application filed September 19, 1921. Serial No. 501,634.

To all whom it may concern:

Be it known that I, WILLIAM H. THORPE, a citizen of the United States, residing at Mount Vernon, New York, have invented 5 certain new and useful Improvements in Portable Lamps, of which the following is a specification.

The object of this invention is to provide a portable electric lamp of light, compact 10 construction so devised that the parts which might be easily broken or injured, such as the lamp bulb, wire and plug, are entirely enclosed and protected by the base and reflector when the lamp is not in use. Such 15 a lamp is especially suitable and convenient for travelling purposes. In addition, the lamp is provided with a clamping device which is also enclosed by the base and reflector and which may be used to attach the 20 lamp to any convenient support. The lamp being designed particularly for travelling purposes, the base and reflector, which protect the other parts are made sufficiently strong to withstand considerable rough 25 usage.

I have shown and described herein one embodiment of my invention, which is the best of which I am at present advised. This 30 form or embodiment is used for the purpose of illustration and should not be taken as limiting for obviously, the invention can be given different embodiments without departing from its spirit.

The embodiment chosen for illustration 35 is shown in the accompanying drawings in which—

Figure 1 is a cross sectional view of the complete lamp when arranged for conveyance of the lamp;

40 Figure 2 is a view similar to Fig. 1 but with the lamp arranged for illumination;

Figure 3 is a plan view of the lamp.

Fig. 4 is a view similar to Fig. 1, except that the reflector and bulb are in illuminating position. Figs. 5 and 6 show modifications.

In the drawings, the reflector 1 encloses the lamp bulb 2, the latter being mounted on an insulated base which is built into the 50 reflector. Two metal contacts in the form of cups 4 and 5 are mounted in the insulating material of the base 3. Metallic connection is made between these cups 4 and 5

to the lamp bulb terminals, these connections not being shown in the drawing. The 55 base of the lamp 6 is provided with a receptacle 7 to hold the lamp bulb and reflector when the lamp is in use, contact being made between the metal cups 4 and 5 and pins 8 and 9, the current being carried 60 to the pins by means of the duplex wire 10 and 11. When the lamp is not in use the duplex wire, which may be from, say eight to ten feet in length, is wrapped around the supporting arms 12 and 13, the plug at 65 the end of the wire being forced into the space between the receptacle 7 and the arm 12.

The base of the lamp also contains a clamping device 14 which is in the position 70 shown in Fig. 1 when it is not in use. When it is to be used it is first revolved 90° (in a horizontal plane) on the pin 15 to the position shown at A and B, Fig. 3, which allows the clamp to clear the lamp base and it is 75 then in a position to be operated. In the design shown, slots are cut in the base at 19 to allow clamp to be turned 90°. The clamp may also be constructed with a hinge attached to one arm so that by opening the 80 hinge 180° the clamp will clear the base without having to cut away slots in the base.

The base 6 is so designed and is of such a shape that it will fit tightly over the reflector port 1 and is held in position by suitable catches 17 and 18 attached to the reflector port of the lamp. Thus, the lamp, 85 wire and clamping device, etc., are entirely enclosed when the lamp is not in use.

When the lamp is to be used, the reflector 90 part is separated from the base, by drawing out the catch 18, and is placed in the receptacle 7 of the base part of the lamp as also shown in the drawing. It should be noted that parts contained in the base are all 95 placed above the bottom of the base part (the wire being passed through a small slot in the base) so that when the clamping device is not used, the lamp may be set on a table, or any flat surface, without any parts, 100 except the base touching the table.

If it is found desirable, the receptacle and lamp bulb base 3 may be so constructed that the lamp bulb and reflector may be revolved, the current conducting contacts between the 105 receptacle and the lamp bulb base would

then be in the form of concentric rings on lamp bulb base 3 making contact with short pins on the receptacle 7 these pins being connected to the conducting wire in a similar manner to that already described.

The invention is not limited to this particular design or construction but includes any similar construction whereby the lamp bulb, wire plug and clamping device are entirely enclosed or protected by the lamp base and reflector, also the invention is not limited to this particular size and shape of lamp bulb but would include any size or shape of electric lamp bulb in use for lighting purposes.

What I claim is:

1. A lamp including a base, a socket removably secured to said base, a reflector attached to said socket, said socket constitut-

ing the sole means of attaching the reflector 20 to the base.

2. The device of claim 1, said socket being seated in a depression in the base.

3. The device of claim 1, said socket being seated in a depression in the base, with 25 electrical connections within said depression.

4. A lamp including a reflector, a socket attached to said reflector, a bulb in said socket, a base having an open bottom, means 30 on said base to receive the socket, said reflector being insertable within the open base to form a closed chamber to protect said bulb.

In testimony whereof I have affixed my 35 signature to this specification.

WILLIAM H. THORPE.
